W. E. HARTBECK.
DRAWER RETRACTING MECHANISM.
APPLICATION FILED FEB. 19, 1917.

1,238,514.

Patented Aug. 28, 1917.

By Watson E. Coburn

Attorney

UNITED STATES PATENT OFFICE.

WILLIAM E. HARTBECK, OF MANCHESTER, MICHIGAN.

DRAWER-RETRACTING MECHANISM.

1,238,514.

Specification of Letters Patent. Patented Aug. 28, 1917.

Application filed February 19, 1917. Serial No. 149,599.

To all whom it may concern:

Be it known that I, WILLIAM E. HARTBECK, a citizen of the United States, residing at Manchester, in the county of Washtenaw and State of Michigan, have invented certain new and useful Improvements in Drawer-Retracting Mechanism, of which the following is a specification, reference being had to the accompanying drawings.

10 This invention relates to certain improvements in drawer retracting mechanism; and it is an object of the invention to provide novel and improved means whereby the drawers may be automatically retracted.

15 It is also an object of the invention to provide a novel and improved device of this general character whereby the drawers may be held against movement under the influence of the retracting means therefor.

20 The invention consists in the details of construction and in the combination and arrangement of the several parts of my improved mechanism whereby certain important advantages are attained and the device 25 is rendered simpler, less expensive and otherwise more convenient and advantageous for use, all as will be hereinafter more fully set forth.

The novel features of the invention will 30 hereinafter be definitely claimed.

In order that my invention may be the better understood, I will now proceed to describe the same with reference to the accompanying drawings, wherein—

35 Figure 1 is an elevational view of an article of furniture constructed in accordance with an embodiment of my invention; and

Fig. 2 is a vertical sectional view taken through the device as herein embodied.

40 As herein disclosed, I illustrate an article of furniture of a bureau or chiffonier type and wherein is embodied the housing or frame structure H of any ordinary or preferred type and with which coacts the sliding drawers D. The drawers D are mounted for movement within the housing or frame H in any desired manner.

45 Positioned rearwardly of each of the drawers D and supported by the side walls 1 of the housing or frame H is the board 2. At substantially its center the board 2 is provided with an opening 3 and arranged sub-

stantially within said opening 3 are the transversely alined pulleys or rollers 4 with which engage the flexible member F.

55 One end of said flexible member F is anchored, as at 5, to the bottom drawer D and for which reason the bottom or lower board 2 is provided with but a single pulley or roller 4. The flexible member F extends 60 upwardly from the lower or bottom drawer D and is disposed over a pulley 6 suspended from the top 7 of the housing or frame H. The member F then extends downwardly and has secured to its free end the weighted 65 member 8.

The flexible member F is also extended around the pulleys 9 carried by the drawers D above the lower or bottom drawer and which pulley is preferably interposed between the pulleys 4 hereinbefore referred to.

70 The member 8 is of such weight as to serve to automatically cause the drawers D to assume a retracted or closed position as is believed to be clearly apparent to those skilled 75 in the art and fully illustrated in Fig. 2 of the accompanying drawings.

In order that the drawers D may be maintained open and held against the action of the member 8, I provide the upper margin 80 of a side wall 10 of each of the drawers with the notches 11 and with which coacts the gravity pawl 12 supported by the housing or frame H preferably at a point adjacent the front thereof. It is also preferred that each 85 of the pawls 12 be provided with a tail-piece 14 extending exteriorly of the housing or frame H through a suitable opening 15 produced in the front thereof. Through the medium of the tail-piece 14 it is thought to 90 be self-evident that when it is desired that a drawer assume a retracted or closed position, it is only necessary to depress the tail-piece 14.

95 From the foregoing description, it is thought to be obvious that a drawer retracting mechanism constructed in accordance with my invention is of an extremely simple and comparatively inexpensive nature and is particularly well adapted for use by reason of the convenience and facility with which it may be assembled, and it will also be obvious that my invention is susceptible 100 of some change and modification without

material departure from the principles and spirit thereof and for this reason I do not wish to be understood as limiting myself to the precise arrangement and formation of the several parts herein shown in carrying out my invention in practice, except as hereinafter claimed.

I claim:

1. In combination with a plurality of members arranged in vertical alinement and mounted for sliding movement in substantially a horizontal path, a stationary support positioned rearwardly of each of the members, guide members carried by said stationary members, a guide member supported independently of the sliding members and at a point thereabove, a flexible member secured to the lowermost of said sliding members and positioned over the last named 20 guiding member, intermediate portions of said flexible member coacting with the guide members carried by the stationary supports and slidably engaged with the first named members above the lowermost of said mem-

bers, and a weighted member engaged with 25 the flexible member.

2. In combination with a plurality of vertically alined members mounted for sliding movement in a horizontal direction, means common to all of said members for 30 imparting movement thereto in one direction, each of said members being provided with a series of notches spaced apart in the same general direction as the direction of travel of the members, a stationary support positioned adjacent the members, and portions carried by the stationary support and co-acting with the notches of the members for holding the members against movement under the influence of the operating 35 means therefor.

In testimony whereof I hereunto affix my signature in the presence of two witnesses.

WILLIAM E. X HARTBECK.
